Atty

UNITED STATES PATENT OFFICE.

EUGENE D. SWIFT, OF CHICAGO, ILLINOIS.

RAILROAD SWITCH POINT AND HEEL PLATE.

Application filed January 6, 1926. Serial No. 79,534.

This invention relates to a railroad switch and concerns itself primarily with the mounting of the movable switch member or point so that the same will always be free to shift. In other words, there is provided a lost motion connection that will never decrease or be taken up by the wearing or biting coaction of parts so that the movable member or point will not be forced to bend when the switch line is operated.

The invention comprises the novel structure and combination of parts hereinafter described and more particularly pointed out and defined in the appended claims.

15 In the accompanying drawings, which illustrate a preferred embodiment of this invention and in which similar reference numerals refer to similar features in the different views:

20 Figure 1 is a plan view of a railroad switch.

Figure 2 is an enlarged horizontal sectional view through the rails 1 and 3 and the heel block.

25 Figure 3 is an enlarged sectional view upon the line III—III of Figure 1.

Figure 4 is a side elevational view of the heel block.

As shown on the drawings:

30 As an exemplification of this invention, there is shown a railroad track comprising the rails 1, 2, 3 and 4, and the movable switch members or points 5 and 6. Between the rails 1 and 3 there is a heel block 7. A

35 similar heel block 7 is positioned between the rails 2 and 4. The points or switch members 5 and 6 respectively form continuations of the rails 4 and 3. An angle member 8 fits between the head and flange of

40 the rail 3 and switch member 6, and a metal strip 9 fits against the web of the rail 1. Suitable clamping bolts 10 and 11 clamp the parts 8, 9, 1, 3 and 7 together. Between the angle member 8 and the heel block 7 adjacent the movable switch member 6, there

45 is a lost motion way 12 to provide for a swinging movement of the switch member 6. This lost motion way is preferably formed by making a gradually increasing recess or groove in the heel block 7, the widest portion of the recess being at the end of the switch member where the greatest arc

of movement takes place. According to this construction the movable switch member 6 will have a fulcrum adjacent the side of 55 the heel block 7 at the rear of said recess. In the present instance, this fulcrum is located between the bolt 11 and the adjacent end of the heel block.

It should be understood that while only 60 the connection of the switch member 6 has been specifically illustrated, the connection of the switch member 5 is the same as can readily be ascertained from Figure 3.

The switch members 5 and 6 are connected 65 by a rod 13 connected to a pull crank lever 14 pivoted at its apex to a suitable support and operated by a link 15.

It will be obvious that as the switch members are laterally shifted, they will fulcrum 70 upon the sides of the heel blocks, the confined ends thereof swinging in the lost motion way 12. It will be appreciated that a very firm connection is thus-wise produced, which always provides a swinging movement, since it is impossible for the lost motion way to decrease or disappear by the moving together of parts as commonly occurs in the structures now in use. 75

I am aware that many changes may be 80 made, and numerous details of construction may be varied through a wide range without departing from the principles of this invention, and I therefore do not purpose limiting the patent granted hereon, otherwise 85 than necessitated by the prior art.

I claim as my invention:

1. A switch structure for a railroad comprising a pair of stationary rails, a heel block positioned between said rail and a 90 switch member fulcrumed intermediate its ends against said block, said block being cut away beyond said fulcrum to allow said switch member to swing.

2. In a railroad switch, a pair of stationary rails, a heel block positioned between said rails, a switch member fulcrumed upon one side of said block, said block being fashioned to provide a tilting space adjacent said switch member beyond the fulcrum 100 point thereof.

3. In a railroad switch, a pair of rails, a heel block between said rails, one side of said heel block having a gradually increased

recess and a switch member fulcrumed upon the said side of said block and having the portion beyond said fulcrum lying in said recess.

5. In a railroad switch, a pair of co-operative members, a switch member having an end projecting between said members, one

of said members forming a fulcrum for an intermediate portion of said switch member and having a way for swinging movements 10 of the said end of said switch member.

In testimony whereof I have hereunto subscribed my name.

EUGENE D. SWIFT.
